UNITED STATES PATENT OFFICE.

JOHN A. P. ERICKSON, OF NORTHLAND, MINNESOTA.

CANDLE.

1,420,476.

Specification of Letters Patent. Patented June 20, 1922.

Application filed January 19, 1921. Serial No. 438,480.

To all whom it may concern:

Be it known that I, JOHN A. P. ERICKSON, a citizen of the United States, and a resident of Northland, in the county of St. Louis and State of Minnesota, have invented a new and Improved Candle, of which the following is a full, clear, and exact description.

This invention relates to improvements in candles, an object of the invention being to provide a candle which will sparkle and produce a pleasing optical effect.

A further object is to provide a sparkling candle of this character which is primarily adapted for use as an ornament on Christmas trees, birthday cakes, etc., which will be simple and practical in construction, and comparatively inexpensive to manufacture.

With these and other objects in view, the invention consists in certain novel features of construction and combinations and arrangements of parts, as will be more fully hereinafter described and pointed out in the claim.

The accompanying drawing is a view partly in longitudinal section and partly in elevation of my improved candle.

Referring in detail to the drawing, 1 represents the wick of my improved candle. The wick is composed of a suitable number of cotton strings or similar flexible inflammable devices dipped in a mixture of lard or similar substance, and metal filings. The wick is molded into a candle 2 in the usual

manner. The body portion of the candle 2 35 is of tallow, wax, or some other material commonly used for the purpose.

When the candle is lighted the metal filings in the wick will be heated and thrown laterally and upwardly from the candle and fall therefrom in a glowing condition. The color of the sparks will of course depend on the character of the metal filings used, it being desirable to use filings which will emit glowing sparks of a character adapted to 45 contrast strongly with the light of the burning candle.

I am aware that metal filings have been used to throw out sparks from burning torches, and do not claim this idea as my 50 own. I rather wish to cover the idea of a candle in which such filings are normally imbedded and concealed in the wick.

Various slight changes and alterations might be made in the general form and arrangement of the parts described without departing from the invention, and hence I do not limit myself to the precise details set forth but consider myself at liberty to make such changes and alterations as fairly fall 55 within the spirit and scope of the appended claim.

What I claim is:

A spark emitting candle, including an inflammable body portion, a wick embedded 65 in said body portion, and metal filings adhesively associated with said wick.

JOHN A. P. ERICKSON.
